UNITED STATES PATENT OFFICE.

LIONEL M. WOOLSON, OF DAYTON, OHIO, ASSIGNOR, BY MESNE ASSIGNMENTS, TO ECLIPSE MACHINE COMPANY, OF NEW YORK, N. Y., A CORPORATION OF NEW YORK.

ENGINE-STARTING APPARATUS.

Application filed July 10, 1918. Serial No. 244,173.

To all whom it may concern:

Be it known that I, LIONEL M. WOOLSON, a citizen of the United States, and a resident of the city of Dayton, in the county of Montgomery and State of Ohio, have invented an Improvement in Engine-Starting Apparatus, of which the following is a specification.

This invention relates to starting apparatus, and with regard to the more specific features thereof, to means for starting internal combustion engines.

One of the objects of this invention is to provide practical and easily operated means for starting a source of power.

Another object is to provide means of the above type of simple and durable construction which shall be convenient in control and whose action shall be automatic.

Another object is to provide means of the above type whose action shall be relatively easy on the parts.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings wherein are shown one or more of various possible embodiments of the several of this invention, Fig. 1 is a view of starting apparatus, partly in longitudinal section. Fig. 2 is a fragmentary sectional view on a larger scale taken along the line 2-2 of Fig. 1. Fig. 3 is a diagrammatic view showing the electrical circuits and Fig. 4 is a fragmentary view partly in longitudinal section showing a modification.

Similar reference characters refer to similar parts throughout the different views of the drawings.

Referring now to Figs. 1 and 3 of these drawings, there is shown a starting motor having an armature 1 and field coils 2 enclosed in a yoke 3. The armature has a shaft having an extension 4 preferably bearing a transmission of the automatic screw shaft type. The transmission is preferably constructed as follows: A part of the extension 4 of the shaft is threaded as at 5, there being preferably a shoulder 6 at the

junction between the unthreaded part of the extension 4 and the threaded part 5. A pinion 7 adapted to cooperate with geared flywheel 7' is fitted over the unthreaded part of the extension and a nut 8 is threaded on the portion 5. The pinion preferably has an integral hub extension 38 whose free surface is accurately machined at right angles to the shaft, for reasons fully appearing below. A barrel 9 is preferably secured by means, such as screws 10, to nut 8, said barrel having a serrated flange portion 11, the serrations preferably fitting between the teeth of pinion 7, whereby there can be no relative rotation between the barrel and the pinion, though relative longitudinal movement is possible. A relatively strong coil spring 12, whose purpose will appear fully below encircles the extended shaft, is enclosed within barrel 9 and contacts pinion 7 at one end and nut 8 at the other. A stop 13 is preferably formed at the end of threaded portion 5 of the shaft to limit the motion of the power transmission in a direction away from mesh. The stop or adjacent parts are preferably designed to prevent binding of the nut 8, and some means is preferably provided to prevent the nut or its associated parts from creeping. The details of the non-binding stop and of the arrangement for preventing creeping are no part of my present invention and are therefore not shown.

The transmission just described, as is readily seen, permits of no relative rotation between nut 8 and pinion 7, and no auxiliary device is interposed in any part of the transmission for taking up the shock of applying the power of the starting motor to the engine. By my present invention, I achieve shockless operation by permitting a relatively unyielding transmission to electrically control the torque of the motor to bring about a relatively shockless action.

Referring to Figs. 1 and 2, I provide preferably in series with the motor, a resistance 14 separated from the armature and field of the motor by a partition 15. One end of this resistance is preferably connected to a terminal 16 shown grounded, and the other end to an end of the field coil as shown at 17. A lead 19 extends from the field coil at a point electrically contiguous to the end connected at 17 and is electrically connected with post 20 secured to segment 21 which segment is insulated from end head 22, as

shown at 23. Another segment 24 is mechanically and electrically connected to the end head 22. The segment 21 is thus of the same potential as the end 17 of resistance 14, and grounded segment 24 of the same potential as the other end of resistance 14, as appears more clearly in Fig. 3. An annular switch member 25 preferably dished and formed with radial slits 26 preferably encircles shaft extension 4 between the pinion and the end head. A transverse member 27 is, also, preferably slipped over shaft extension 4 being secured to annular member 25, as shown at 28. This transverse member 15 preferably has an opening at each end, through one of which extends stud 29 and through the other stud 30, both studs being rigid with the end head 22. Holding means, preferably cotter pins 31, are provided for 20 preventing the transverse member from coming off the studs. Coil springs 32 are preferably provided, one encircling each stud, contacting the end head at one extremity, and the lower face of the transverse member at 25 the other. These coil springs, as is readily understood, bias the transverse member against the cotter pins and the annular switch member to open position. The operation is substantially as follows: 30 A single contact starting switch S, Fig. 3, being closed, the motor will turn with a relatively low torque, resistance 14 being in circuit therewith. The inertia of the nut 8 and its attached parts will cause it to 35 travel longitudinally along the shaft in the well-known manner pushing pinion 7 through spring 12 until said pinion enters into cooperation with flywheel gear 7'. After initial and before full meshing has 40 taken place, the machined surface of extension 38 on pinion 7 will contact transverse member 27, and nut 8, through spring 12, will continue to push the pinion along the shaft overcoming the resistance of coil 45 springs 32, urging annular switch member 25 into contact with the two segments 21 and 24. This contact, when completed, will short-circuit resistance 14, thus causing the motor to operate at full power. The initial 50 engagement between annular switch member 25, and the segments 21 and 24 is, of course, relatively light and furnishes a correspondingly ineffective electrical contact and as the pinion continues moving by virtue of the 55 longitudinal push imparted by spring 12 from the said position to that where full meshing is effected, it gradually increases the pressure transmitted to said annular switch member, thus making the contact 60 more and more effective and causing a gradual cutting out of resistance 14. As shown in Fig. 1, nut 8 may still move through a small range after the switch 25 has substantially short-circuited resistance 14. Nut 65 8 will, therefore, continue through such small

range until it strikes shoulder 6, transmitting increased pressure to switch 25 by way of spring 12, thus taking care of any irregularities in the switch construction, and assuring a complete elimination of resistance 14. The machined surface 38 on pinion 7 assures a substantially uniform application of pressure at all parts of the periphery of the annular switch member 25. The torque of the motor after initial meshing of the 70 gears is once effected will thus be gradually increased to its maximum to gradually and relatively shocklessly apply its power to cranking the engine. After the engine operates under its own power, the pinion 7 80 is rotated faster than the shaft 4 and causes the nut 8 to overrun the threaded portion 5 bringing about automatic demeshing in well-known manner.

In Fig. 4, I have shown a modification of 85 my invention. Here the mechanical parts of the transmission are the same as in Fig. 1. Instead of the ordinary resistance shown in Fig. 1, I provide a carbon pile 33 consisting of a plurality of slightly dished carbon 90 annuli 34 surrounding shaft 4 and insulated therefrom and from the end head as at 85. A bridging contact switch member 36 also preferably encircles shaft 4', and preferably bears an insulating disk 36' against which the pinion may contact. This switch, when pressed against insulated plate 37 and grounded plate 38 on end head 22 of the motor will short-circuit the carbon pile. The pile is connected in circuit substantially as 100 resistance 14 in Figs. 1 and 3.

In operation, pinion 7 after partial meshing will gradually compress pile 33, gradually cutting out the resistance in circuit with the motor, causing the motor to exert a gradually increasing torque which reaches its maximum, after bridging switch 36 entirely short-circuits the pile at which time the pinion 70 is in full mesh with flywheel 70'.

In the operation of automatic starters of 110 the screw shaft form, as is well-known, the teeth of the pinion sometimes fail to align properly with those of the flywheel gear so that butting of teeth may occur. When such butting occurs, the pinion being arrested against movement into mesh with the gear is inoperative for the purpose of effecting an increased torque of the motor. The pinion being arrested against the face of the flywheel, the nut 8 will continue travelling 115 along the threaded portion 5 compressing spring 12 until the nut 8 grips the shaft with sufficient security to turn with said shaft to rotate pinion 7 slightly into proper alignment with the flywheel whereupon compressed spring 12 will suddenly expand, pushing pinion 7 partially into mesh with the flywheel whereupon travel into full mesh 120 and cutting out of the resistance may proceed as described above. It is thus seen 125 130

that by my invention butting of teeth can only occur while the motor is running at low torque and the torque of the motor cannot increase until the butting condition is relieved and the gears have traveled partially into mesh. If the electric motor were permitted to operate at a relatively high torque at a time when teeth are butting end to end, it is obvious that a stripping of gear teeth might result when the pinion is again brought into motion.

Although Figs. 1 and 4 show screw-starters of the inboard type, and although this is my preferred form, it is to be understood that this invention may be applied to good advantage to outboard, as well as inboard forms of starters. Fig. 3 diagrammatically shows an outboard form by way of example.

Although the specific form of the screw shaft transmission shown and described is my preferred form, it is also to be understood that my invention is applicable to other forms of transmission of various types automatic as well as manual.

It will thus be seen that there is herein described apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In combination, an engine, a driven gear connected thereto, an electric motor normally having a resistance in circuit therewith, a shaft driven by said motor, a substantially unyielding driving member threaded on said shaft and having gear teeth, said teeth being adapted to cooperate with and drive said gear, but normally offset therefrom, means in the path of said driving

member at a point beyond the adjacent surface of said driven gear, and adapted to be controlled by said driving member to gradually remove said resistance after initial meshing has taken place, and means to the rear of said driving member for effecting proper alignment of gear teeth should butting occur.

2. In a starter for gas engines, and the like, in combination, with a gear operatively connected with an engine, an electric motor, a driving pinion, a resilient member to yieldingly transmit a shifting impulse from said motor to said pinion and to bring said pinion into mesh with said gear, a member for affecting the circuit of said motor, having a bias in one direction, and in the path of said shiftable element, whereby said bias will be overcome by the action of said motor to alter the circuit of said motor, and a rigid power connection for rotation of said pinion by said motor.

3. In a starter for gas engines and the like, in combination, with a gear operatively connected with an engine, an electric motor, operating with relatively low torque, a driving pinion normally out of engagement with said gear, a resilient member for transmitting an impulse to urge said pinion into mesh with said gear and for bringing about an increased torque of said motor after initial meshing has taken place, and relatively rigid means for rotating said pinion to crank the engine.

4. In a starter for gas engines and the like, in combination, a motor, a threaded shaft driven thereby, a driving pinion upon said shaft, a nut threaded upon said shaft and to the rear of said pinion, means connecting said nut and pinion to rotate in unison, a compression spring interposed between said nut and said pinion to yieldingly transmit the shifting impulse from said nut to said pinion, a resistance in series with said motor, and a switch in the path of said driving member for effecting a short circuit of said resistance after said pinion enters into mesh.

In testimony whereof, I have signed my name to this specification this tenth day of June, 1918.

LIONEL M. WOOLSON.
